METHOD OF PURGING AND WASHING
SOLIDS IN A CENTRIFUGAL

Charles A. Olcott, Montclair, N. J.

Application June 27, 1935, Serial No. 28,782

13 Claims. (Cl. 210—67)

This invention relates to the separation of solids from liquors in which they are contained and more particularly to the separation and washing of solids in a centrifugal dryer and it is an object of this invention to provide an improved method of separating such solids from the liquors in which they are contained, washing the solids to remove retained traces of the containing liquors and removing the wash liquid without drying the solids to such an extent that they are hard and difficult to remove from the dryer. It is also an object of this invention to provide an improved means for carrying out the method.

15 In the drawing—

Fig. 1 is a substantially diagrammatic vertical section of a centrifugal dryer for preparing materials in accordance with this invention;

Fig. 2 is a view taken as a section on the line 2—2 of Fig. 4, showing in substantially diagrammatic form a means used in controlling the separator of Fig. 1 in carrying out this invention;

Fig. 3 is a front view of the dial shown in Fig. 4; and

25 Fig. 4 is a partial side view of the control means shown in Fig. 2.

In the following description, for the purposes of illustration, the method is set forth as applied to the separation of sugar from its mother liquor but it is to be understood that the method is not limited in its operation to the separation of such solid only as it can be used in the separation of other solids such as salt, borax and other similar solids similarly separated from the containing liquors.

In the production of sugar, a centrifugal dryer is used to remove the mother liquor or molasses from the sugar. The centrifugal force, to a great extent, overcomes the tendency of the molasses to adhere to the sugar crystals but, regardless of the speed of rotation of the dryer some molasses adheres in the form of a film on the crystals. To remove the molasses film from the sugar crystals the sugar is washed by spraying with a suitable washing liquid, as water or a syrup, while still in the rotating dryer. In this washing step, the washing liquid removes the molasses film from the crystals leaving a substantially pure sugar, and it also dissolves a certain amount of the sugar so that it is desirable to effect the washing with the use of the smallest possible quantity of the washing liquid in order to keep down the expense of recovering the sugar from the washing liquid. After the washing is completed the rotation of the dryer is continued to

remove as much as possible of the washing liquid, but the sugar crystals retain a film which is substantially a pure solution of sugar in water. This film coats the crystals and if the rotation of the dryer is carried to the point where air is passed between the crystals sufficiently to dry the film, the sugar of this film is recrystallized and serves to cement the sugar crystals into a mass which is removed from the dryer only with considerable difficulty.

While a high rotative speed is desirable for separating the mother liquor from the sugar because of the more nearly complete removal of the mother liquor effected thereby and the smaller quantity of washing liquid required to remove what remains, it has not previously been used, however, because of the impossibility of stopping the rotation of the dryer before the air passing between the crystals dries the film left upon removal of the washing liquid and cements the crystals in the dryer into substantially a solid mass. To overcome these objections the removal of the mother liquor and the washing of the sugar has usually been carried out with the basket of the dryer rotating at about 900 R. P. M. for a 48 25 inch diameter basket.

In the preparation of sugar in accordance with this invention the separation of the sugar from the mother liquor is at a high speed of rotation of the dryer and the washing of the sugar is 30 at a lower speed, that is, a speed low enough to prevent the recrystallization of the sugar in the washing liquid retained by the sugar and the bonding together of the sugar crystals thereby. In its practical application the separation of the 35 mother liquor or molasses from the sugar is carried out with the basket of the dryer rotating at about 1200 R. P. M. Upon completion of the removal of the molasses the speed of rotation of the basket is decreased gradually to about 950 40 R. P. M. and while the speed of the basket is decreasing the washing liquid is applied, the period required for the reduction of the speed of the basket being made sufficiently long to permit of the desired amount of washing liquid being applied; so that the basket attains the desired reduced speed at the time, or immediately after, the supply of washing fluid is cut off. During the time the washing liquid is being drawn off the speed of rotation of the basket is further reduced until it is below 900 R. P. M. and the danger of drying the film of the washing liquid between the crystals and cementing the material into a solid mass is removed. The speed of the basket is then further reduced to about 600 50 55

R. P. M. for discharging the contents of the basket.

In order to provide for the separation of solids from the liquids which contain them in accordance with this invention the operation of the basket of the dryer and the control thereof may be by any usual and suitable means which admit of the basket being operated at the desired speeds for the proper lengths of time.

10 In the drawing, however, for the purpose of illustration the basket 1 of the dryer is shown operated by a two-speed motor 2 through a centrifugal clutch 3 and shaft 4 as in the patent to Mackintosh, No. 15,115, reissued May 31, 1921.

15 Washing liquid may be supplied to the basket 1 through the nozzle 4 and pipe 5 from a suitable source of supply, the liquid being supplied under constant pressure for definite periods of time, and the supply of the liquid may be controlled by any 20 suitable means as, for example, the controlling means shown in the patent to Steps, No. 1,947,679, Feb. 20, 1934, or the patent to Roberts, 1,224,095, April 24, 1917.

The motor 2 may be of any suitable type and 25 arranged for operation on either an alternating or a direct current circuit. In the drawing the motor is shown as of the induction or slip ring type operable on an alternating current circuit with connections from the rotor 6, through slip 30 rings 8 and 10, leads 12 and 14, fixed contact 16, and movable contact 18 to complete a circuit of variable resistance through resistance 20. In a motor of the type described varying the current in the rotor varies the tendency of the rotor to 35 rotate with the field produced by the alternating current in the stator and provides a means for controlled regenerative braking in reducing the speed of rotation of the dryer from the high speed at which the mother liquor or molasses is removed 40 to the lower speeds at which the sugar is washed, the washing liquid removed and the sugar broken up for removal from the basket. When the motor controller, not shown, is operated to change the operation of the motor from its higher to its lower 45 speed, that is, from a speed of 1200 R. P. M. to 600 R. P. M. the momentum of the basket 1 serves to drive the rotor 6 as a generator, the load thereon and the resulting braking effect being determined by the resistance of the circuit including the adjustable resistance 20. Where the time during 50 which the washing liquid is supplied is controlled, as in the Steps patent previously referred to, the shaft 22 which operates the movable contact 18 may be the shaft in the Steps construction which 55 serves to operate the means for varying the time during which the washing liquid is supplied. Where this arrangement is used, as in Fig. 4, the resistance in the rotor circuit is arranged so that when the shaft 22 is operated to lengthen the time 60 during which the washing liquid is supplied, the movable contact 18 is shifted to increase the resistance in circuit with the rotor 6, reducing the current in the rotor and the braking effect therefrom and decreasing the rate of deceleration of 65 the rotor and basket, the resistance being so proportioned that the speed of the dryer will decrease from the speed at which the mother liquor is removed to the speed at which the washing liquid 70 is removed in a slightly longer period than is required for supplying the washing liquid. Operating the shaft 22 in the opposite direction to decrease the time during which the washing liquid is supplied will operate the movable contact 18 75 to decrease the resistance in the rotor circuit and

increase the rate of deceleration of the rotor but the time required to reduce the speed of rotation of the dryer to the speed at which the washing liquid is removed is always slightly in excess of the time during which the washing liquid is supplied. While the resistance 20 is described as being regulated by the shaft which regulates the time during which washing liquid is supplied, it is to be understood that separate shafts independently operated may be used and while the motor 2 is described as being an alternating current motor it is to be understood that a direct current motor could be regulated in the same manner.

In Fig. 1 there is shown diagrammatically the wiring for operating the motor 2 at high and low speeds as an alternating current motor, a single phase only of the alternating current circuit being shown. Current is supplied from a source of power by the leads L¹ and L² to a double throw switch 25 which in one position connects the source of power through leads 27 and 28 to the high speed winding 26 and in the other position connects the source of power through leads 31 and 32 to the low speed winding 30. The switch 25 is also provided with contacts which complete a shunt through leads 34 and 35 around the resistance 20 when the source of power is connected to the high speed winding 26 but which contacts leave the shunt open when the source of power is connected to the low speed winding 30.

What is claimed is:

1. In a process of separating solids from a containing liquor the steps of centrifuging the liquor from the solids at a high speed of rotation and 35 treating the solids with a washing liquid while decreasing the speed of rotation from the high speed to a predetermined lower speed.

2. In a process of separating solids from a containing liquor the steps of centrifuging the liquor from the solids at a high speed of rotation, treating the solids with a washing liquid while decreasing the speed of rotation to a predetermined lower speed and centrifuging the washing liquid from the solids at a lower speed. 45

3. In a process of separating solids from a containing liquor the steps of centrifuging liquor from the solids at a high speed of rotation, treating the solids with a washing liquid while decreasing the speed of rotation and centrifuging the washing liquid from the solids while further decreasing the speed. 50

4. In a process of separating solids from a containing liquor the steps of centrifuging the liquor from the solids at a constant high speed, washing the separated solids while centrifuging at a lower speed and completing the centrifuging of the washing liquid from the material at a still lower speed. 55

5. In a process of separating sugar crystals from a containing liquor, the steps of centrifuging the liquor from the solids at a high speed of rotation, treating the solids with a washing liquid, and decreasing the speed of rotation during 65 the washing period to a speed less than that at which the air currents dry and cement the crystals.

6. In a process of separating sugar crystals from a containing liquor, the steps of centrifuging the liquor from the solids at a high speed of rotation, treating the solids with a washing liquid, decreasing the speed of rotation during the washing period to a speed less than that at which the air currents dry and cement the crys- 70 75

tals and centrifuging the washing liquid from the crystals at a still lower speed.

7. The combination with a centrifugal dryer of means for rotating said dryer at predetermined different speeds, means for supplying a predetermined amount of washing liquid to the dryer in a predetermined period, braking means for providing a predetermined deceleration of the dryer from its higher operating speed during the period in which the washing liquid is supplied and means connecting said liquid supplying means and braking means for simultaneously adjusting the rate of deceleration of the dryer in accordance with changes in the period during which liquid is supplied.

8. The combination with a centrifugal dryer of means for operating said dryer at a plurality of predetermined speeds, means for supplying a predetermined amount of washing liquid to the dryer in a predetermined period, braking means for reducing the speed of the dryer from its higher speed of rotation to a predetermined speed intermediate the predetermined operating speeds in the washing period and means connecting said liquid supplying means and braking means for simultaneously adjusting the braking period in accordance with changes in the volume of washing liquid supplied.

9. The combination with a centrifugal dryer of means for rotating said dryer at a high speed for purging the basket contents of the mother liquor and a low speed for discharging the basket contents, means for supplying a predetermined amount of washing liquid to the dryer in a predetermined period, braking means for reducing the speed of the dryer during the washing period from its high speed to a speed less than the speed at which the contents of the basket cement and means connecting said liquid supplying means and braking means for simultaneous adjustment thereof.

10. The combination with a centrifugal dryer of means for rotating said dryer at a high speed for purging the basket contents of the mother

liquor and a low speed for discharging the basket contents, means for supplying a predetermined amount of washing liquid to the dryer in a predetermined period, braking means for reducing the speed of the dryer during the washing period from its high speed to a speed less than the speed at which the contents of the basket cement and means connecting said liquid supplying means and braking means for simultaneously increasing the volume of the washing liquid and lengthening the period required for speed reduction.

11. The combination with a centrifugal dryer of means for rotating said dryer at different speeds, means for supplying washing liquid to the dryer for a predetermined period, braking means for reducing the speed of the dryer from its higher speed to a predetermined speed intermediate said different speeds in the washing period and means connecting said liquid supplying means and braking means for simultaneously adjusting the washing period and the deceleration of the dryer.

12. The combination with a centrifugal dryer of an induction motor for operating said dryer at different speeds, means for supplying washing liquid to the dryer for a predetermined period, means for including an electrical resistance in the circuit of said rotor for effecting a predetermined speed reduction in the washing period and means for simultaneously varying the washing period and said resistance for maintaining the relation of speed reduction period to the washing period.

13. The combination with a centrifugal dryer of an induction motor for operating said dryer at different speeds, means for supplying a predetermined volume of washing liquid to the dryer, regenerative braking means for reducing the speed of rotation of the dryer from the higher speed to a predetermined speed in the washing period and means for simultaneously varying the volume of washing liquid supplied and the speed reduction period.
